UNITED STATES PATENT OFFICE

GERRIT LOUIS GOEDHART, OF THE HAGUE, NETHERLANDS.

MEANS FOR PROTECTING VESSELS FROM MINES.

1,296,949.

Specification of Letters Patent.

Patented Mar. 11, 1919.

Application filed February 11, 1918. Serial No. 216,536.

To all whom it may concern:

Be it known that I, GERRIT LOUIS GOEDHART, residing at The Hague, the Netherlands, have invented certain new and useful 5 Improvements in Means for Protecting Vessels from Mines, of which the following is a specification.

It has already been proposed to protect vessels from contacting with anchored 10 mines by surrounding them with a metallic net or screen, similar to torpedo nets as attached to men-of-war and having for their purpose to prevent the vessels from being hit by launched torpedoes.

15 Such nets, which extend a considerable distance below the water level and even below the keel of the vessel, cause great resistance when moving through the water, so that they materially reduce the speed of the 20 vessel.

This disadvantage is nearly completely obviated by the device according to the present invention.

This arrangement consists of a steel protecting rope or cable which approximately 25 at the depth of the keel of the vessel and otherwise as deep as possible but at least at a depth of five meters, is stretched between a system of booms from a point in front of 30 the ship to points at both sides of the latter; near the latter points tools are provided in or to the steel rope, the said tools having for their purpose to render inactive the mines encountered by the vessel and whose 35 anchoring chains are deflected by the protecting rope, either by detaching them from their anchors or by dragging them along together with their anchoring cables.

The mines may be detached from their 40 anchoring chains by means of a so-called mine cable pistol or by any other cutting gear for mine cables or chains; the dragging along of the mines encountered by the vessel may be effected by a hook or a clutch 45 for engaging the mine cable or chain. In the latter case the mine should be removed with great care; in the first case the mine breaks adrift whereby it becomes inactive.

The drawing illustrates one form of embodiment of the invention:—

Figure 1 shows the bow of a protected vessel in plan view, together with the system of booms and the protective rope stretched between the ends thereof;

55 Fig. 2 shows a side elevation.

1 is the front boom which in the example given is formed by a T-shaped beam having a length of, say, 12 meters, the said boom being pivotally connected with the bow and supported by a seamless tube 2, which is 60 also pivotally connected with the bow and which is provided with two rollers for guiding it along the flanges of the boom 1, so as to engage a positive stop when the boom assumes its lowest position. 65

Two systems of strengthening cables 3 and 4 between the boom 1 and the brackets 5 at either side of the prow insure the required lateral strength.

In a similar manner the booms 6 and 7 are 70 connected with the sides of the vessel and strengthened. These booms are suspended by ropes from the yard of the foremast (not shown) and provided with rollers 8 and 9 respectively over which the protective rope 75 passes.

The device as a whole, or each of its parts separately, may be raised by means of ropes and winches. The strengthening cables of the booms should preferably remain taut 80 when the gear is raised; this will be the case when the connections between these cables and the vessel are in a straight line with the pivotal connections of the booms, such as is shown in the drawing. 85

The protective rope 10 runs from a winch on the fore-deck over rollers 11, 12 at the end of the boom 1, over the rollers 8 and 9 of the booms 6, 7 respectively, and then passes under the keel to the opposite side of the vessel, where it is also connected with a winch. The latter winch serves for bringing the cutting gear 13, which is attached to the protective rope 10 near the side booms, into its proper place. The 95 winch on the fore-deck has for its purpose to stretch the protective rope.

The mines whose anchoring cables or chains contact with the protective rope 10 are deflected to either side of the vessel 100 where they are rendered inactive by the gear 13.

What I claim as my invention is:

1. The combination with a vessel, of a system of booms pivotally connected to the vessel, a single rope stretched under water by said booms from a point in front of the vessel to points at both sides thereof, a tool connected to said rope and adapted to engage the cable of an anchor mine or detach 110

it from its anchor and means for moving said rope to bring the tool to proper position.

2. The combination with a vessel, of a system of booms, pivotally connected to the vessel, means for raising and lowering said booms, a single rope stretched under water by said booms from a point in front of the vessel to points at both sides thereof, a tool 10 connected to said rope and adapted to engage the cable of an anchor mine or detach it from its anchor and means for moving said rope to bring the tool to proper position.
- 15 3. The combination with a vessel, of a T-shaped boom pivoted to the front of the vessel, a tube pivoted to the front of the vessel and having a sliding connection with the boom, booms pivoted to the side of the 20 boat, a single rope stretched under water by said booms from a point in front of the vessel to points at both sides thereof, a tool connected to said rope and adapted to engage the cable of an anchor mine or detach

it from its anchor and means for moving 25 said cable to bring the tool to proper position.

4. The combination with a vessel, of a T-shaped boom pivoted to the front of the vessel, a tube pivoted to the front of the vessel and having rollers engaging the sides of the T-shaped boom and forming a sliding connection therewith, booms pivoted to the sides of the vessel, a single rope stretched under water by said booms from a point in 30 front of the vessel to points at both sides thereof, a tool connected to said rope and adapted to engage the cable of an anchor mine or detach it from its anchor and means for moving said cable around the ends of 35 said booms to bring the tool to proper position.

In testimony whereof I have affixed my signature in presence of two witnesses.

GERRIT LOUIS GOEDHART.
